G. E. MOLYNEUX,
WHEEL LOCK FOR QUICK DETACHABLE WHEELS,
APPLICATION FILED JUNE 13, 1921.

1,417,276.

Patented May 23, 1922.

UNITED STATES PATENT OFFICE.

GEORGE E. MOLYNEUX, OF BAYONNE, NEW JERSEY.

WHEEL LOCK FOR QUICK-DETACHABLE WHEELS.

1,417,276.

Specification of Letters Patent. Patented May 23, 1922.

Application filed June 13, 1921. Serial No. 477,024.

To all whom it may concern:

Be it known that I, GEORGE E. MOLYNEUX, a citizen of the United States, residing in Bayonne, county of Hudson, and State of New Jersey, have invented a new and useful Improvement in Wheel Locks for Quick-Detachable Wheels, of which the following is a description.

This invention relates to quick detachable wheels for automobiles, and similar vehicles, and, particularly, has reference to a means for locking together the inner and outer hub-shells of the wheels so as to prevent the wheel from slipping off in case of accident or in the absence of the hub-cap.

Among the objects of my invention may be noted the following: to provide a direct and positive lock between the inner and outer hub-shells of a wheel; to provide a means for preventing the wheel from coming off, should the hub-cap come off for any reason, as by becoming loose by failure to lock the same in place by the usual hub-cap locking mechanism; to provide a means by which to prevent the wheel from shifting or becoming loose on the inner hub-shell, should the hub-cap be loose, be removed, or accidentally be dropped, or displaced; to provide a means operating as a lock between the inner and outer hub-shells and which prevents the two said shells from losing their concentric relation in the event the hub-cap is removed or should accidentally drop off; to provide a means which requires that the proper concentric relation of the inner and outer hub-shells shall be infallibly established before the hub-cap can be placed or adjusted and locked in position; to provide a means carried by the inner hub-shell which will insure the user against accidents of a frequently fatal character by the loss of a wheel resulting from the loss of the hub-cap, which often occurs at high speed of the vehicle; to provide a means by which the user is enabled to determine that the inner and outer hub-shells are properly set before he places, or can place, the hub cap in position and lock the same as required, thus making it necessary to properly place the wheel and outer-shell relatively to the inner-shell before the hub-cap can be locked; to provide a lock between wheel and inner hub-shell which, when the wheel is slipped into place, automatically locks the wheel in running position and prevents the wheel from shifting position or coming off even though the hub-cap may not

be in place; and to provide a simple, strong, durable and compact arrangement for locking the inner and outer hub-shells together, preventing them from being accidentally separated, preventing them from losing their concentric arrangement, and for other purposes and functions set forth in the foregoing.

With the above objects in view and others which will be detailed during the course of this description, my invention consists in the parts, features, elements and combinations thereof hereinafter described and claimed.

In order that my invention may be clearly understood, I have provided drawings wherein:

Figure 1 is a sectional elevation showing the hub-shells or members in their cooperative relation, with the hub-cap in place, and embodying a form of my invention which I have found satisfactory in practice;

Figure 2 is a section on the line 2—2 showing details of the form of my invention illustrated in Figure 1; and

Figure 3 is an elevation of the locking and centering ring illustrated in Figures 1 and 2.

It has been found in practice, referring particularly to wire-wheels, that after the wheel has been set in place with its outer-shell or hub in cooperative relation with the inner-shell or hub, so that the one may drive the other, and that the hub-cap can be placed, it sometimes happens, through either carelessness, neglect, or unfamiliarity with the hub-cap locking means, that the hub-cap will not be tightly set in place or will be so set that the locking means cannot be properly set, so as to keep the hub-cap in place during the running of the vehicle. In such instances, the hub-cap will eventually work loose, drop off, and serious accidents will occur by the dropping off of the wheel. Also, it has been found to be difficult to set the wheel with its outer hub-shell accurately and properly with reference to the inner hub-shell and bring about the proper concentric relation of the two for proper and easy driving purposes. This difficulty results in the further objection that the hub-cap cannot be properly set and oftentimes the parts will not be properly adjusted, resulting in accidents to the vehicle and to the persons therein. It is a great desideratum, therefore, that some means be employed for accurately setting the wheel and its hub-shell in place in proper cooperative relation to

the inner hub-shell and in such position as to enable the hub-cap to be properly set in place and locked; and it is also a great desideratum that, in the event the hub-cap, 5 for any reason, should drop off during the running of the vehicle, the wheel shall not come loose or drop off or lose its concentric relation to the inner hub-shell. My invention, as illustrated in the drawings, avoids 10 all the objections above noted, and brings about the desirable results and functions indicated through the medium of a direct connection between the inner hub-shell and wheel and which operates as a positive lock 15 between the two.

Referring to the drawings, the numeral 1 indicates the inner hub-shell having any usual form of driving means for co-action with the wheel-shell or outer hub-shell. 20 The forward end of the inner hub-shell is provided at its outer end with external screw threads 3 upon which the hub-cap 4 is turned and is adapted to be set and held or locked in place by any usual form of hub-cap locking means such, for example, as that shown in my Patent #1,324,513, granted Dec. 9, 1919. The hub-cap locking means has been omitted in order to avoid confusion in the drawings and also that my wheel or shell-lock may be better understood and accentuated. The hub-cap 4 at its outer end is provided with an enlargement 5, which is flared outwardly, so as to engage closely with the flared end 6 of the wheel or outer hub-shell, the said flared end being shown as having an inturned flange with which the enlargement 5 of the hub-cap engages and cooperates; and it will be seen that, when the parts are in proper cooperative relation, as 30 shown in Figure 1, the face of the hub-cap and the face of the outer hub-shell are flush or in the same vertical plane, which latter is tangential to the end 6, this being also one of the features of my invention illustrated in 40 my said Patent #1,324,513 above referred to. It is understood that the outer hub-shell 2 has the wire spokes attached thereto and carries the rim and other members of the wheel, and that, when the said outer hub-shell is removed, the entire wheel is removed. 50 My wheel or shell-lock, as shown in the figures of the drawing, consists of a ring member 7 the inner diameter of which is sufficient to enable it to freely encircle the 55 screw-threaded end of the inner hub-shell 1, and the outer diameter of which is sufficient to enable it to operate freely within the elongated cylindrical portion 8 of the outer hub-shell. That is to say, when the faces of 60 the ring are normal to the cylindrical portion 8 of the outer hub-shell and to the cylindrical portion 9 of the inner hub-shell, all the parts, viz., ring 7, shell 1, and shell 2 can be freely moved relatively; but, when the ring 7 65 is canted, it will bind upon the cylindrical

portion 9 of the inner hub-shell and lock the inner and outer hub-shells rigidly together. Thus the ring 7 becomes a locking medium and also a centering medium for the inner and outer hub-shells, preventing the wheel 70 from being displaced or removed until the proper relation between the ring and the two shells is established.

To provide for the foregoing functions and modes of operation, the outer hub-shell 75 on the inner surface of its cylindrical member 8 is provided with two parallel, elongated, arc-shaped lugs 11 and 12 affording a space between them throughout their length sufficient to enable the ring 7 to freely move 80 between the two and be tilted or canted to the desired extent, as shown in Figure 1. The ring 7 is pivotally mounted centrally in the two lugs, having for the purpose a large aperture 13 through which passes a pivot pin 85 14, the aperture 13 being much larger in diameter than the pivot pin, which is anchored in the two lugs 11 and 12, thus enabling the ring 7 to be swung and canted inwardly on its pivotal support between the 90 said two lugs. At a point diametrically opposite the lugs 11 and 12, the inner surface of the cylindrical portion 8 of the outer hub-shell is provided with an apertured lug 15, the same being located entirely in advance of 95 or outwardly relatively to the lug 12, or, in other words, in a plane parallel to the face of said lug 12 and passing diametrically through the two hub shells. In a corresponding position, or diametrically opposite the aperture 13, the ring 7 is provided with an aperture 16 through which a bolt 17 passes having a head 18 at its inner end back of the ring 7 and an adjustable collar 19 at the front of the ring, the bolt 17 also passing 100 through the lug 15 and through the flared end 6 of the outer hub-shell, as presently described. The body of the bolt between the ring 7 and lug 15 has a coiled expansion spring 21 surrounding the same. Thus, the 110 spring, at one end, engages the lug 15, and, at its opposite end, engages the collar 19 and normally tends to force the ring 7 inwardly into the canted position shown in Figure 1. It will be noted that the distance between the 115 collar 19 and the headed end of the bolt 18 is sufficient to allow the ring 7 to have freedom of movement so as to enable it to be brought to a position normal to the surface of the inner shell portion 9, and it will also 120 be noted that the aperture 16 is sufficiently greater in diameter than the diameter of the bolt 17 to give ample clearance between the two to enable the ring to operate as required. The spring 21 is preferably of a length such 125 that it becomes completely compacted against the lug 15 when the ring 7 is drawn outwardly to a position normal to the portion 9 of the inner hub-shell, thus acting as a stop to prevent the ring being shifted too far out- 130

wardly, or to a position such that it would again clutch and lock the wheel on the inner hub-shell. When the spring is thus compacted, the wheel can be readily slipped off the hub of the inner-shell. The ring 7, at opposite points on its circumference equidistant from the apertures 13 and 16, is provided with ears 22 adapted to slide against the inner surface of the cylindrical portion 8 of the outer hub-shell, the function of said ears being to hold the ring 7 steadily in position and prevent it from sagging laterally on its pivot. This also results in quietude during the running of the vehicle, avoiding rattling and tendency to tug or strain upon the inner end of the bolt 17.

Viewing Figure 1, it will be seen that the normal position of the ring 7, under the expansive force of the spring 21, is indicated to be at an inclination to the hub-shells, the spring 21 causing the ring 7 to automatically assume the position shown and normally tend to assume said position under all conditions, and it will be understood that, in this position, the ring 7 operates as a clutch to grip the circumference of the inner hub-shell cylindrical portion 9 and maintain its grip thereon throughout all operating conditions. When it is desired to place the wheel on the car, the same is slid over the inner hub-shell until the driving parts of the two shell members are in cooperative relation, and while this is being done the ring 7 will engage the outer end of the inner hub-shell and will be shifted outwardly until it stands normal to the cylindrical portion 9. In this position, the outer hub-shell can slide freely into position relative to the inner hub-shell, the ring maintaining its position normal to the cylindrical portion 9, after the spring 21 is compressed, until the co-acting parts of the inner and outer hub-shells are co-ordinated; but, it will be understood that the spring operates, by expansion, always with a tendency to shift the ring 7 into locking engagement with the inner hub-shell, so that when the wheel has reached its innermost position and the driving parts of the hub-shell have been coordinated, the ring 7 will then automatically shift to the position shown in Figure 1, where it grips or clutches the circumference of the cylindrical portion 9 of the inner hub-shell and locks the wheel thereto, the spring 21 normally tending to compel the ring to hold such position and gripping relation and to resist all tendency of the two hub-shells to separate or shift longitudinally. Any strain upon the wheel tending to shift the same relatively to the inner hub-shell will make the ring 7 grip the latter and lock the wheel securely. The hub-cap 5 can now be screwed onto the threads 3 of the inner hub-shell portion 9 until the flared member 5 is in proper cooperative relation with the

flared member 6 of the outer hub-shell, at which time the hub-cap lock should spring into proper position behind the flange of the flared portion 6 to lock the cap from longitudinal movement.

The bolt 17 is extended forwardly, or outwardly, through a groove 23 in the inturned flange and end 6 of the outer hub-shell, said groove following the contour of said end 6. The end of the bolt 17 lies in said groove 75 and follows its contour, as at 24, and terminates in an extension 25 forming a handle projecting beyond the shell, the terminal of the groove, as at 26, affording ample room for movement of said handle outwardly when shifting the ring 7. The spring 21 keeps the handle properly housed and prevents its engagement with external objects, even though the end of the hub should be encountered.

When it is desired to remove the wheel, a wrench applied to the face of the hub-cap will retract the hub-cap lock, enabling the hub-cap to be unscrewed from the cylindrical portion 9 of the inner hub-shell and removed. With the hub-cap removed, the handle 25 of the bolt 17 can be grasped or pressed upon by the fingers, and the bolt drawn forwardly so as shift the clutch ring 7 from its canted or inclined position, shown 95 in Figure 1, to a position normal to the shell portion 9 of the inner hub, thus releasing the latter and the locking engagement between the inner and outer hub-shells, and enabling the wheel to be drawn forwardly over the 100 inner hub-shell and removed.

It will now be understood that, in accordance with my invention, I have provided an independent lock in the form of a clutch between the inner and outer hub-shells of a 105 wheel, or between the wheel and its support, and that this lock or clutch between the two members is independent of the lock which secures the cap to the wheel and prevents the cap from being removed from the inner 110 hub shell. Consequently, I have provided a means which will prevent the wheel or outer hub-shell from being removed from, or becoming displaced relatively to, the inner hub-shell, and which prevents the wheel 115 from accidentally coming off under any circumstances, should, for any cause whatever, the hub-cap be loosened or drop off. It will also be seen that the said clutch or lock between the hub-shells prevents the shifting 120 of the one relatively to the other, thus maintaining the two hub-shells in their proper concentric relation. This is important under all conditions and particularly under the condition of loss or dropping off of the hub-cap which would ordinarily bring about a 125 change in relation of the wheel and inner hub-shell; that is to say, ordinarily, the two members would shift relatively, causing the wheel to drop down on the inner hub 130

shell or upon the axle, thus causing uneven wear, and grinding, and tendency to destruction of the parts in contact.

Having thus described my invention, 5 what I claim and desire to secure by Letters Patent is:

1. In combination with the hub-shell of a quick detachable wheel and the inner hub-shell cooperative therewith, a locking device 10 carried by one of the shells and adapted to lock the two shells together.
2. In combination with the hub-shell of a quick detachable wheel and the inner hub-shell cooperative therewith, a clutch lock 15 carried by one of the shells and adapted to clutch and lock the two shells together.
3. In combination with the hub-shell of a quick detachable wheel and the inner hub-shell cooperative therewith, a locking medium 20 interposed between the two shells and pivotally mounted on one of them and adapted to lock said shells together.
4. In combination with the hub-shell of a quick detachable wheel and an inner shell 25 cooperative therewith, a pivotally mounted means between the two shells adapted to maintain the concentric relation of the two shells under all running and adverse conditions.
- 30 5. In combination with the hub-shell of a quick detachable wheel and the inner hub-shell cooperative therewith, a lock mounted and adapted to operate between the two shells, said lock being automatically shiftable angularly relatively to the two shells and their longitudinal axes so as to lock the shells together.
6. A combination of elements such as set forth in claim 5, wherein the automatic lock 40 is under spring control, which normally tends to maintain the same in locking condition.
7. A combination of elements such as set forth in claim 5, wherein the automatic locking device is carried entirely by the hub-shell of the wheel.
8. In combination with the hub-cap of a quick detachable wheel and the inner hub-shell cooperative therewith, a locking device 50 carried by the wheel hub-shell and surrounding the inner hub-shell, and adapted to clutch the latter to hold the two in cooperative relation.
9. In combination with the hub-shell of 55 a quick detachable wheel and the inner hub-

shell cooperative therewith, a locking means adapted to hold the two hub-shells cooperatively together consisting of a ring pivotally mounted on the wheel hub-shell and surrounding the inner hub-shell, and means operating upon the said ring for causing the latter to grip the said inner hub-shell.

10. A combination of elements such as set forth in claim 9, wherein the means operating upon the ring includes a headed bolt 65 passing through the ring, a collar surrounding the bolt, a spring surrounding the bolt and engaging the collar, and also engaging a lug upon the hub-shell through which the bolt passes.

11. In combination with the hub-shell of a quick detachable wheel and an inner hub-shell cooperative therewith, a locking ring pivotally mounted on the wheel hub-shell and surrounding the inner hub-shell, means 75 normally tending to hold the ring in locking engagement with the inner hub-shell, and means carried by the ring for holding the ring steadily in position and preventing it from sagging laterally relatively to the hub-shells.

12. In combination with the hub-shell of a quick detachable wheel and the inner hub-shell cooperative therewith, a locking medium for said shells interposed between 85 them, said medium including means causing it to automatically go into locking action, and an extension terminating outside the wheel hub-shell for manual manipulation of said medium.

13. In combination with the hub-shell of a quick detachable wheel and the inner hub-shell cooperative therewith, a locking medium for said shells interposed between them, said medium including means normally tending to shift the same at an angle to the inner hub-shell to grip the latter, and an extension terminating outside the wheel hub-shell near its outer end for manual manipulation of said medium.

14. In combination with the hub-shell of a quick detachable wheel and the inner hub-shell cooperative therewith, a locking medium for said shells interposed between them, said medium including a reciprocable bolt having a handle housed in the wheel hub-shell, a pivotally mounted ring, and interacting means between the ring and bolt for controlling the action of the former.

GEORGE E. MOLYNEUX.
